FRANK F. STARR, OF DAYTON, OHIO, ASSIGNOR TO DELCO-LIGHT COMPANY, OF DAYTON, OHIO, A CORPORATION OF DELAWARE

ELECTRICAL APPARATUS

Application filed September 30, 1929. Serial No. 396,055.

This invention relates to internal combustion engines and more particularly to the automatic controls for the supply of fuel thereto.

One of the objects of the present invention is to provide a fuel discharging device for priming an internal combustion engine during the starting thereof, and to arrange the device so that the greatest amount of fuel will enter the engine upon initiation of the starting operation and will gradually diminish its supply as the engine gains speed until the device is rendered inoperative after the engine attains a speed of a predetermined amount. One manner of carrying out this idea is to provide a fuel discharging device which includes fuel absorbing means, and to arrange the device so that the fuel absorbing means will be placed in the path of air leading to the engine, during the cranking of the engine and to remove the fuel absorber to a fuel well during the operation of the engine, or when the engine is inoperative. In this manner the air flowing to the engine will carry the greatest amount of fuel from the absorbing means at the instant the absorbing means is placed in the path of air and will gradually carry less fuel as the fuel in the absorbing means diminishes.

Further objects and advantages of the present invention will be apparent from the following description, reference being had to the accompanying drawings, wherein a preferred form of the invention is clearly shown.

In the drawings:

Fig. 1 is a diagrammatical illustration of the present invention; and

Fig. 2 is a sectional view of the carburetor and of the fuel discharging device.

Referring to the drawings, the numeral 20 designates an internal combustion engine having a fuel intake 21 which is in communication with a passageway 23 formed by a carburetor 24. Any suitable means may be employed for supplying fuel to the carburetor 24. In the present case I provide preferably, a fuel pump 25 connected with a supply tank 27 by pipe 28. The fuel pump 25 is provided with an outlet pipe 29 which is connected with the fuel bowl 33 of the carburetor 24.

The carburetor includes preferably, a main jet 35 through which fuel may be supplied to the engine by the suction created by the engine cylinders, and if desired, an overflow outlet 37 connected with a return pipe 38 which is connected with the supply tank 27 may be used to return excessive fuel to the supply tank to thus maintain a predetermined level of fuel in the carburetor bowl 33, which level is indicated at 40. It is to be understood, however, that other means for maintaining a predetermined level of fuel in the carburetor bowl may be employed, such as, for example, the conventional float valve.

In order to aid in starting the engine 20, I have provided a fuel discharging device 50. The device 50 includes a plunger 51, an electro-magnet 52 for actuating the plunger, a housing 53 for the electro-magnet, and a well 55. The plunger 51 is adapted to carry on one end thereof a fuel absorbing means 57, preferably felt. During self-operation of the engine and when the engine is inoperative, the plunger 51 is adapted to partially immerse the felt 57 in the fuel contained in the well 55. In this manner the felt will absorb the fuel and become entirely saturated therewith. A cover 60 for the well 55 is carried by the plunger 51 to prevent fuel from being withdrawn therefrom during engine operation. The well 55 is adapted to be supplied with fuel from the bowl 33 of the carburetor 24 through a pipe 62. By this arrangement fuel will flow from the bowl 33 through the pipe 62 and rise in the well 55 to a level indicated at 40a which level will be the same as the level in the carburetor bowl 33. Thus the overflow outlet 37 will normally tend to maintain a predetermined level of fuel in the bowl 33 and the well 51.

The fuel discharging device 50 is adapted to be carried by a casting 70 which is connected with the carburetor 24 by screws 71. The casting 70 is adapted to form a passage 72 through which the plunger 51 extends, and is provided with an opening 74 to allow the passage of air through the passageways 72, 23 and the intake 21 to the engine.

The energization of the electro-magnet 52 will cause the upward movement of the

plunger 51 to thus place the saturated felt in the path of air flowing to the engine 20. The plunger 51 is so constructed that when the uppermost portion 78 thereof engages the housing 53, the lowermost portion 79 of the felt 57 will be substantially flush with the top of the well 55. By this arrangement the suction created by the engine cylinders will not withdraw fuel from the well 5 10 but will withdraw the fuel from the saturated felt at first, relatively rich mixture will be supplied to the engine due to the fuel carried off from the felt by passing air and as the engine continues the fuel mixture will 15 gradually become leaner as the supply of fuel in the felt is depleted. The device is computed so that proper mixture is supplied to the engine. After the engine becomes self operative and attains a certain speed the 20 electro-magnet will become deenergized to allow the plunger 51 to descend by gravity to immerse the felt in the fuel in the well 55 and to cover the well with the cover 60.

A motor-generator 80 having a shunt field 25 winding 81 and a starting series field winding 82 is used for cranking the engine, receiving current from a storage battery 83, and is adapted to maintain the battery in a charged condition during engine operation. 30 In order to complete a circuit between the battery and the motor-generator a starting switch 85 must be closed. The circuit from the battery through the motor-generator may be traced as follows: battery 83, wire 87, current coil 87a, electro-magnet 52, wire 88, 35 series field 82, motor-generator 80, wire 90, switch 85 and wire 91 to the other side of the battery.

Preferably, the starting switch 85 may be 40 controlled automatically in a similar manner as disclosed and described in my co-pending application, for electrical apparatus Serial No. 351,346 filed March 30, 1929. After the engine becomes self operative 45 and attains a certain speed, the series winding 82 and the electro-magnet 52 will become short-circuited. This may be accomplished by means of a reverse current relay 100 and a series shorting switch 105. Thus, during the 50 operation of the system the current passing through the current coil 87a will be reversed in direction from that during cranking operation to thus change the polarity of the relay side plates 107 and 108 to cause an armature 55 110 of relay 105 to change its position and cause the engagement of contacts 111 and 112. The armature includes a shunt winding 116 connected across the battery 83. The armature also includes a pair of side 60 plates which are polarized by the shunt winding 116. Thus a reversal of current in the coil 87a changes the polarity of the side plates 107 and 108, causes like poles of said side plates and like poles of the armature side 65 plates to repel to cause the armature to

change position. The engagement of contacts 111 and 112 complete a circuit through a coil 120 of switch 105. The circuit through coil 120 may be traced as follows: Wire 125 which is connected to wire 87, relay side 70 plates, contacts 111 and 112, coil 120 and wire 127 which joins wire 90 leading to the negative side of the generator. The energization of coil 120 causes the engagement of contacts 130 and 131. The closing of contacts completes a circuit to the battery through wire 133, contacts 130 and 131, wire 134 and wire 87. The circuit through wires 133 and 134 offers less resistance than the 75 circuit through series winding 82 and coil 80 52 to thus short circuit the winding 82 and coil 52. Thus the fuel discharging device will remain operative to supply fuel to the engine during cranking thereof, and gradually become leaner in its supply as the 85 speed of the engine increases and will be rendered inoperative when the speed thereof attains a certain value.

While the form of embodiment of the invention as herein disclosed constitutes a preferred form, it is to be understood that other forms might be adopted, all coming within the scope of the claims which follow.

What is claimed is as follows:

1. An internal combustion engine comprising in combination, means for supplying priming fuel to the engine, said means including fuel absorbing means, and means for placing the fuel absorbing means in the path of air flowing to the engine for a predetermined length of time only. 90

2. An internal combustion engine comprising in combination, means for supplying priming fuel to the engine, said means including fuel absorbing means, and electrical- 100 ly operated means for placing the fuel absorbing means in the path of air flowing to the engine. 105

3. An internal combustion engine comprising, in combination, an engine intake, means for supplying priming fuel to the engine intake, said means including fuel absorbing means, and means for placing the fuel absorbing means in the path of air flowing to the engine intake for a predetermined length of time only. 110

4. An internal combustion engine, comprising in combination an engine intake, a carburetor connected to the engine, means for supplying priming fuel to the engine, said means including fuel absorbing means, and means for placing the fuel absorbing means in the path of air flowing through the carburetor for a predetermined length of time only. 120

5. An internal combustion engine comprising in combination, a fuel well, means for supplying priming fuel to the engine disposed in said fuel well, said means includ- 130 ing fuel absorbing means, and means for

placing said fuel absorbing means in the path of air flowing to the engine for a predetermined length of time only.

6. An internal combustion engine comprising in combination, a fuel well, means for supplying priming fuel to the engine disposed in said fuel well, said means including fuel absorbing means, and electrically operated means for placing said fuel absorbing means in the path of air flowing to the engine.

7. An internal combustion engine comprising in combination, an engine intake, a fuel well carried by the intake, means for supplying priming fuel to the engine disposed in said fuel well, said means including fuel absorbing means, and means for placing said fuel absorbing means in the path of air flowing to the engine for a predetermined length of time only.

20 8. An internal combustion engine comprising in combination, a fuel feeding device for the engine comprising a fuel jet, a fuel bowl for supplying fuel to the jet, means for maintaining a predetermined level of fuel in said bowl, and a fuel discharging device comprising a well, a duct connecting the well and bowl whereby the fuel level therein is controlled by the fuel level in the bowl, means for supplying priming fuel to the engine disposed in the well, said means including fuel absorbing means, and means for placing said fuel absorbing means in the path of air flowing to the engine.

35 9. An internal combustion engine comprising in combination, an engine intake, a fuel feeding device for the engine comprising a fuel jet connected with the engine intake, a fuel bowl for supplying fuel to the jet, means for maintaining a predetermined level of fuel in said bowl, and a fuel discharging device comprising a well connected with the engine intake, a duct connecting the well and bowl whereby the fuel level therein is controlled by the fuel level in the bowl, fuel absorbing means disposed in the well, and means for placing said fuel absorbing means in the path of air flowing to the engine.

40 In testimony whereof I hereto affix my signature.

50 FRANK F. STARR.
